UNITED STATES PATENT OFFICE.

ITHAMAR M. JUSTICE, OF DAYTON, OHIO.

HEATING SYSTEM FOR DRIERS.

1,105,566.

Specification of Letters Patent. Patented July 28, 1914.

Application filed March 11, 1912. Serial No. 682,976.

To all whom it may concern:

Be it known that I, ITHAMAR M. JUSTICE, a citizen of the United States, residing at Dayton, Ohio, have invented certain new and useful Improvements in Heating Systems for Driers, of which the following is a full, clear, and exact description.

My invention relates to a type of driers wherein air is heated and circulated around and among the objects to be dried, and while my improvements are applicable to driers in general, I will illustrate them in connection with a drier for clay products.

It is well known that to heat air it is necessary to bring it into contact with a heated solid. Therefore, an essential feature in a drier is a source of heat. This is usually a furnace, and one of the objects of my invention is to construct a furnace in such manner as to heat the greatest possible area of solid surface with a given amount of fuel.

Another object is to bring the air into contact with as much of the heated surface of the furnace as possible.

A further object is to introduce air, preferably heated, at a point where, by mixing with unconsumed fuel gases a combustible mixture is formed, which burning increases the heating capacity of the furnace. These and other advantages are attained by the construction shown in the accompanying drawings, in which:

Figure 1 is an elevation of the discharging end of battery of driers. Fig. 2 is an elevation of the other end of the same battery. Fig. 3 is a longitudinal section on line 3—3, Fig. 1. Fig. 4 is a mutilated plan of the battery. The levels at which the several sections in this figure are taken are indicated by numbers and letters, the former referring to other figures and the latter to the particular section line on that figure. Fig. 5 is an enlarged elevation of the lower portion of two sections of the discharging end of the battery, with the front wall of one section removed. Fig. 6 is a section on line 6—6, Fig. 7 a section on line 7—7, and Fig. 8 a section on line 8—8 of Fig. 3. Fig. 9 is a transverse section on line 9—9, Fig. 5.

Similar numerals refer to similar parts throughout the several views.

Referring more particularly to Fig. 2, the doors 25—25—25 cover the openings to tunnels 26; each tunnel has a track on which cars carrying the clay products are run into

the tunnels. When the products are dry, the cars are drawn out at the discharging end. Doors 27 close the discharging ends of the tunnels. Below the track at the discharging end of each tunnel a furnace 30 is located. This furnace has the usual combustion chamber, 31, grate 32, feed door 33 and ash pit 34. When so equipped it is adapted to burn coal, wood, etc. It is to be understood, however, that my invention is not limited in its application to furnaces burning the fuels mentioned. The products of combustion pass over a bridge wall 35 into an expansion chamber 36, and from there into the flue 37. This flue, which is substantially horizontal, runs to the receiving end of the drier where it connects with a transverse horizontal flue 38. This flue terminates at each end in a flue 39 which leads into the stack 40.

The expansion chamber is divided by a baffle wall 41, whereby the products of combustion are forced into the lower part thereof. It will be noted that the expansion chamber is quite large: This is to enable the products of combustion to expand and pass slowly through the chamber, which gives better opportunity for the walls of the chamber to take up the heat. Moreover, the chamber being large, its walls afford a large area of surface for heating the air which passes into the drier. The inlet and outlet being at the top of the expansion chamber, and the baffle wall extending nearly to the bottom thereof, the products of combustion are brought into contact with a very large proportion of the inclosing wall.

At each side of the combustion chamber, at about the base of the arch which forms the dome, a tube 42 is embedded in the wall. One end of each tube is open to the atmosphere (see Fig. 4) and the other end, after making a turn, opens into the space above the bridge wall 35. Air drawn in through these tubes becomes heated by the heat of the walls surrounding them. This heated air mixing with the unburned gases, forms a combustible mixture, which being ignited by the flames from the furnace, increases the heat in the expansion chamber.

The width of the furnace, expansion chamber, and flue is preferably made the same, and being narrower than the tunnel leaves a narrow space, 50, on each side thereof. A cover 51 extending from the top of the furnace to each tunnel wall converts

these spaces into air ducts. In Fig. 9 it will be seen that the cover 51 is continuous for a considerable distance, beyond which it is pierced by openings 52. Now referring 5 to Fig. 4 it will be seen that the cover is finally discontinued, leaving the flue free standing in the space between the walls 53 of the tunnel.

The receiving end of each tunnel is provided with an opening 54 into the stack 40. 10 Because of the tendency for hot air to rise and the stack being of considerable height, a suction is created which draws cold air into the ducts 50 through openings 55 at 15 their front ends. This air is confined to the ducts by the cover 51 and in its passage therethrough becomes heated by contact with the hot walls of the furnace, and expansion chamber. Baffle walls 56 are built 20 into the ducts which compel the air to traverse a far longer course than it would if they were not there. Moreover, the air is thereby brought into contact with practically all of the surface of the furnace and 25 chamber walls. A portion of the air passes up through the openings 52 and the remainder rises into the tunnel through the continuous opening beyond. The support for the tracks in the tunnel being transverse 30 bars 57 there is practically nothing to impede the circulation of air in the tunnel.

A compartment is formed above the combustion chamber 31 by a wall 60 and cover 61; the former not quite reaching to the latter, an opening 62 is formed. Openings 63 in the front wall admit cold air to the compartment, which becomes heated and passes out at opening 62. A partition formed by a baffle wall 64 built out from each tunnel 40 wall partially divides the compartment and lengthens the course of the air through the compartment. The air which passes through this compartment supplies the portion of the tunnel above the expansion 45 chamber not served by the air which enters at openings 55.

Having stated the objects of my invention and described a preferred construction whereby these objects are attained, it is to be understood that minor changes from the construction shown may be made while remaining within the scope of the invention described.

What I claim is as follows:

55 1. In a heating system for driers the combination of a heating element comprising: a furnace, an expansion chamber which is divided into two parts by a baffle wall, and a substantially horizontal flue, the three parts

of the heating element being in horizontal 60 succession and bounded by rectilineal side walls; a horizontal air duct adjacent to and coextensive with each side wall, each wall forming one wall of the adjacent duct, an inlet for air at one end of each duct, and baffles extending alternately upward from the bottom and downward from the top of each duct around which air must pass in traversing the ducts; the top of each duct having a succession of apertures beginning 70 at a point beyond where the flue taps the expansion chamber, the tops being entirely removed therebeyond.

2. In a heating system for driers a furnace having an upper chamber isolated from 75 products of combustion, a pair of baffles extending toward each other from its sides and dividing the chamber into two parts whose only communication is through a narrow space between the opposing edges of said 80 baffles; inlet apertures in the upper part of the front wall of the chamber, one of them close to each side wall, and a horizontal slit at the top of the rear wall of the chamber 85 for the emission of heated air.

3. In a heating system for driers the combination of a heating element comprising: a furnace, an expansion chamber which is divided by a baffle wall into two parts, and a substantially horizontal flue, the three 90 parts of the heating element being in horizontal succession and bounded by rectilineal side walls; a horizontal air duct adjacent to and coextensive with each side wall, each wall forming one wall of the adjacent duct, 95 an inlet for air at one end of each duct, and baffle walls extending alternately upward from the bottom and downward from the top of each duct around which air must pass in traversing the ducts, the top of each duct 100 being removed from a point beyond where the flue taps the expansion chamber; and a chamber above the furnace only having a pair of baffles extending toward each other from its sides and dividing the chamber into 105 two parts whose only communication is through a narrow space between the opposing edges of the baffles, inlet apertures in the front wall of the chamber, one of them close to each side wall, and a horizontal slit 110 in the rear wall of the chamber for the emission of heated air.

In testimony whereof I affix my signature in the presence of two subscribing witnesses.

ITHAMAR M. JUSTICE.
